UNITED STATES PATENT OFFICE.

JACOB J. BUSENBENZ, OF GRAND RAPIDS, MICHIGAN, ASSIGNOR TO DIFFERENTIAL CLOCK CO., OF CHICAGO, ILLINOIS, A CORPORATION OF ILLINOIS.

REGULATOR FOR LEVER TIME-MOVEMENTS.

1,144,026.

Specification of Letters Patent. Patented June 22, 1915.

Application filed January 2, 1915. Serial No. 85.

To all whom it may concern:

Be it known that I, JACOB J. BUSENBENZ, a citizen of the United States, residing at Grand Rapids, in the county of Kent and 5 State of Michigan, have invented a new and useful Improvement in Regulators for Lever Time-Movements, of which the following is a specification.

My invention relates to an improvement 10 in regulators for the hair-springs of clocks of the so-called lever type, and watches; and it is my object to provide a simple and durable construction of such regulator which shall enable regulation of a time-movement 15 equipped with it to be effected with great facility and with the utmost nicety.

In the accompanying drawing, Figure 1 is a broken face view of a clock frame, with the dial removed and showing my improved 20 regulator in front elevation; Fig. 2 shows the same by a broken view in side elevation, with the clock-dial in section, and Fig. 3 is a section on line 3, Fig. 1.

The views illustrate the parts on an ab- 25 normally large scale.

The frame 4, of which one side is presented in Fig. 1, covered by a dial 5, shown in Fig. 2, supports the mechanism of a clock, of which only sufficient is illustrated in the 30 drawing to enable my improvement and its operation to be readily understood. The parts shown of the clock-mechanism are the balance-staff 6 carrying the balance-wheel 7, and the hair-spring 8. On the outer face of 35 the front member of the frame, near its upper end, is journaled a segmental gear 9 having a curved arm 10 extending from it at one side of the journal and terminating in a longitudinally slotted extension 11 project- 40 ing across the top of the outer coil of the hair-spring, which coil passes through the slot and is fastened at its adjacent end to the frame, as usual. The extension bears at the upper edge of its slot downwardly against 45 the outer coil. By turning the gear 9 in one direction on its pivot, therefore, the effective length of the hair-spring is augmented, and it is shortened by turning the gear in the opposite direction. For turning the gear a 50 worm 12 meshes with it, the worm-shaft, which carries on one end a peripherally serrated wheel 13 projecting, for access, through an opening (Fig. 2) in the dial, be-

ing spring-supported. The spring 14 sup- 55 porting the worm is shown to comprise a horizontal lower member 14^a provided on one end with a depending ear 14^b, through which the spring is fastened to the frame, and a vertical member 14^c, of general cross form, terminating at its upper end in a 60 tongue 14^d; and the section involving the cross-piece and tongue is offset backwardly, the cross-piece being provided on its ends with forwardly projecting perforated ears 14^e forming bearings for journaling the 65 worm-shaft. In the front member of the frame 4 is an opening 15 of the three different cross-sectional dimensions represented in Fig. 1. The hand-wheel 13 projects through this frame-member in the larger 70 section of the opening, the offset-section of the spring-member 14 projects backwardly through the intermediate section of the same and the tongue 14^d is thereby caused to bear flatwise resiliently against the rear 75 face of the frame-member above that section of the opening, and the worm works in the relatively narrow, third section of the opening. The worm-gear regulator is thus 80 readily accessible for operating it, at the face of the time-piece, by turning the wheel 13 in the required direction to cause the worm to actuate the gear 9 for moving the finger to adjust the spring 8.

The primary importance of spring-sup- 85 porting the worm is to keep it tightly in engagement with the segmental gear and thereby frictionally hold the wheel 13 and gear against too ready or accidental turning. The nicety with which the spring 8 may be 90 regulated by means of my improved regulator is readily apparent; and this nicety is of particular importance with any time-movement which is accurate, in the sense of not varying greatly in time-keeping, as 95 is the clock of my Patent No. 973,854, dated October 25, 1910, for use with which I have more immediately designed my present improvement.

I realize that considerable variation is pos- 100 sible in the details of construction thus specifically shown and described, and I therefore wish to be understood as not in- tending by illustrating a single, specific or preferred embodiment of my invention, to 105 be limited thereto.

What I claim as new and desire to secure by Letters Patent is:—

1. In combination with a time-movement, a regulator comprising a journaled gear having an arm extending into movable engagement with the outer coil of the hair-spring of said movement, and a spring-supported worm in driving engagement with said gear.
  - 10 2. In combination with a time-movement, a regulator comprising a segmental gear journaled on the movement-frame and having an arm extending into movable engagement with the outer coil of the hair-spring of said movement, a spring-support on said frame, and a worm journaled on said support to mesh with said gear.
  - 15 3. In combination with a time-movement, a regulator comprising a segmental gear journaled on the front member of the movement-frame and having an arm provided with an extension movably engaging the outer coil of the hair-spring of said movement, an opening in said frame-member, a spring-support secured on said frame-member to extend into said opening, and a worm
  - 20
  - 25
- having a hand-wheel-carrying shaft journaled on said support at said opening to engage the worm with said gear.
4. In combination with a time-movement, 30 a regulator comprising a segmental gear journaled on the front member of the movement-frame and having an arm provided with a slotted extension movably engaging in the slot the outer coil of the hair-spring 35 of said movement, an opening in said frame-member, a spring-support having a lower member secured near one end to said frame-member and an upright cross-shaped member terminating in a tongue, said cross-shaped member having an offset section extending backwardly in said opening to bear said tongue against the rear face of said frame-member and being provided with journal bearings, a worm on a shaft journaled in said bearings to engage the worm with said gear, and a hand-wheel on the shaft in said opening.

JACOB J. BUSENBENZ.
